UNITED STATES PATENT OFFICE

127,748

DESIGN FOR A SLIP

Sam Landau, New York, N. Y.

Application April 19, 1941, Serial No. 100,508

Term of patent 3½ years

To whom it may concern:

Be it known that I, Sam Landau, a citizen of the United States, residing at Manhattan, in the county of New York and State of New York, have invented a new, original, and ornamental Design for a Slip, of which the following is a specification, reference being had to the accompanying drawing, forming part thereof.

Fig. 1 is a front view of a slip showing my new design;

Fig. 2 is a rear view thereof; and

Fig. 3 is an enlarged fragmentary front view of the upper portion of the slip shown in Fig. 1.

The characteristic feature of my design resides in the combination of the specific heart and floral embroidery arranged on the bust portion of the slip disclosed, in association with a lace edging across the top and around the hem.

I claim:

The ornamental design for a slip, substantially as shown and described.

SAM LANDAU.
